INVENTOR:

William B. Rood,

By MacLeod, Balm, Copeland & Dike ATTYS.

UNITED STATES PATENT OFFICE.

WILLIAM B. ROOD, OF WARE, MASSACHUSETTS, ASSIGNOR TO OTIS COMPANY, OF WARE, MASSACHUSETTS, A CORPORATION OF MASSACHUSETTS.

UNDERGARMENT.

Application filed May 11, 1921. Serial No. 468,514.

To all whom it may concern:

Be it known that I, WILLIAM B. Rood, a citizen of the United States, residing at Ware, county of Hampshire, State of Massachusetts, have invented a certain new and useful Improvement in Undergarments, of which the following is a specification, reference being had therein to the accompanying drawings.

10 My invention relates to union undergarments or combinations. The object of the invention is to provide a construction of garment, particularly of the seat flaps which, while affording an ample seat opening, will 15 close automatically; that is, without conscious effort on the part of the wearer; and furthermore so that the natural strains placed upon the garment by the ordinary movements of the wearer, as in walking, 20 standing, bending over or stooping down, will tend to close the seat opening rather than to open it. These desirable results are attained by the application of the principle that a straight line is the shortest distance 25 between two points, and that when a strain is placed upon the free edge of the seat piece, it will tend to assume a straight line, and therefore may, if properly placed, be employed to pull the seat flap sidewise into position to close the seat opening.

The invention herein described may be embodied in undergarments for men, women or children, but, in the drawings, is shown as employed in men's garments. It will be 30 understood, however, that the adaptation of the garment to women's and children's requirements involves merely the cutting of the garment to fit the figure of the prospective wearer.

40 In the accompanying drawings, I have shown a novel closure for the upper corner of the seat flaps, but I have not claimed the same in the present application, as this forms the subject-matter of an application filed May 11, 1921; Serial No. 468,515.

The invention will be fully understood from the following description when taken in connection with the accompanying drawings, and the novel features thereof will be 45 pointed out and clearly defined in the claims at the close of this specification.

In the drawings, Fig. 1 is a front view and Fig. 2 is a back view of a man's union

undergarment embodying my invention in the preferred form. 55

Fig. 3 is a rear view of the garment shown in Figs. 1 and 2, the seat flaps being drawn apart.

Fig. 4 is a plan view of the two seat flaps.

Fig. 5 shows the two seat flaps superimposed upon each other in the position which they occupy before being sewn into the garment.

Fig. 6 shows my invention embodied in an athletic union suit made of woven fabric 65 such as nainsook.

Fig. 7 is a rear view of a union undergarment embodying my invention but having the upper edges of the two seat flaps permanently secured to the body of the garment. 70

Fig. 8 is a rear view of a modified form of union undergarment embodying my invention.

Fig. 9 is an enlarged view of the novel 75 stay employed at the bottom of the seat opening.

Referring now to the drawings, the body portion of the garment is shown at 11, and in the form shown in Figures 1 to 5 inclusive, is of tubular knit fabric. The fly opening is shown at 12 and is closed with buttons in the ordinary manner.

The back of the body is slit along the median line from the point *a* which is above 85 the waist line downwardly in the ordinary manner. Two seat pieces are provided, (see Figure 4) the outer seat piece being designated 13 and the inner seat piece 14. These

seat pieces are of the same shape but one is 90 reversed as compared with the other. They can, therefore, be cut from the same pattern which is a decided advantage in manufacturing the garments. The vertical sides

b, *c*, *d* and *e* of the seat pieces are nearly 95 parallel with each other, though diverging slightly toward the bottom of the seat piece. In Figure 4, I have shown the position occupied by the two seat pieces when being cut from the fabric. In this position the seat

piece 13 is right side up while the other is bottom side up. The edge *b* of the outer seat flap 13 forms one margin of the outer seat opening and the edge *e* of the inner seat flap 14 forms one margin of the inner

100 seat opening. I have designated the lower 105

edge of the outer seat flap *f*, and of the inner seat flap *g*. The upper edge of the outer seat flap is designated *h* and the upper edge of the inner seat flap is designated *i*.

5 The edge *d* of the inner seat flap and the edge *c* of the outer seat flap are sewn to the respective edges of the slit in the body portion 11 of the garment, and the lower edges *f* and *g* of the two seat flaps are superimposed as shown in Figure 5 and are stitched into the leg inseams 15 and 16, being turned up in front as shown in Figure 1.

I have designated the bottom point of the free edge of the outer seat flap *j* and the upper point of the said free edge *k*. Correspondingly the lower point of the inner seat opening is designated *l* and the upper point *m*. The two lower points *j* and *l*, as will be seen from the drawings, are located in the 20 respective inseams of the leg 15 and 16 while the upper points *k* and *m* are located on opposite sides of the median line of the garment, and about half way between the median line of the garment and the respective 25 sides thereof.

It will also be noticed that these points *k* and *m* are lower than the point *a* so that the upper edges of the seat flaps slope downwardly and outwardly toward the sides of 30 the garment. It will also be seen that when the garment is laid out flat as shown in Figure 2, the points *k* and *j* are both on the same side of the median line, and at a considerable distance from it so that the entire 35 free edge of the outside flap is well on one side of the median line of the garment and in general about parallel with it.

Likewise the free edge of the inside flap is similarly placed on the opposite side of the 40 median line and in general about parallel with it.

The arrangement of these seat openings is a very important feature of the present invention. The seat flaps are cut so that the 45 edges *b* and *e* will be a little short rather than slack, and therefore in the ordinary movements of the wearer whether he stands erect or stoops over, this tends to approach a straight line and thus pulls the respective 50 seat flaps sidewise closing the openings. This action is further assisted by the fact that the points *k* and *j* lie well away from the median line of the garment so that the free edge of the seat opening tends to lie 55 along the side of the wearer and across the outside of the buttock rather than along the median line of the back and over the high point of the buttock or on the inside of the crotch.

60 Similarly the position of the free edge of the inside flap is such that the strain imposed on the edge tends to close the opening. I find in practice that it is not necessary to make the seat flaps either tight or loose, since 65 the natural action of the parts when the

garment is constructed as shown and described herein closes the seat openings automatically and holds both flaps in smooth position across the thighs and through the crotch.

70 In the preferred form of my invention, I make the upper edges *h* and *i* of both seat flaps with hems *n* in which are placed straps *o* and *p* secured to the body of the garment at their ends. In practice both ends of the strap *p* and the inner end of the strap *o* are secured permanently to the body of the garment, but I provide the outer end of the strap *o* with a button and button-hole *q* by which the strap is detachably secured to the body of the undergarment.

75 It will be understood that the hem of each seat piece is slidable on the respective strap and therefore when it is necessary to open the seat opening the hem may be slid toward the median line, thereby enlarging the seat opening.

80 Since the outer end of each of said straps is lower than the inner end and since a slight strain is placed on the free edges of the respective seat flaps, the tendency of the upper free corner of the hem is to work down and close the seat opening. I find in practice that even though the seat opening 85 may not be pulled closed by the wearer after it has been opened, it will soon work closed, owing to the slight strain on the free edges of the seat openings.

85 For the purpose of preventing the body 90 fabric of the garment tearing about the bottom of the fly opening as has commonly been the case with knit garments of this type owing to the fact that knit fabric is relatively weak crosswise of the wale, I use a novel stay 25 of the shape shown in Figure 9. 95 This stay is cut with the wale running transversely and is stitched along the line *v* into the inseam 15, 16 and is stitched to the body along the lines *y* and *z* so that it takes the 100 strain which would otherwise come on the body fabric itself.

105 Referring now to Figure 7, there is shown 110 therein a garment similar to the garment already described except for the fact that the novel closure for the upper edge of the seat flap is not employed but on the contrary the seat flaps are stitched along the lines *r* and *s* to the body portion of the undergarment. I find that under certain conditions such a 115 garment is just as satisfactory as the garment shown in Figure 1.

120 In Figure 6 is shown a garment similar to that shown in Figure 7, but made of nainsook or other woven fabric and provided with a waist band 17 of elastic material. In this garment the upper edges of the seat flaps are sewn to the lower edge *t* of the 125 waist band of elastic material.

130 In Figure 8 I have shown another undergarment, the inner seat flap 18 of which is

permanently attached along its upper edge *u* to the body portion of the garment while the outer seat flap 19 is provided with a strap and button closure as shown at 20, 5 Figure 8.

What I claim is:—

1. An improved union undergarment comprising a body portion and inner and outer seat pieces, one longitudinal edge of 10 each of said seat pieces being secured to the body of the garment and the other longitudinal edges of said seat pieces being free to form inner and outer edges of a seat opening, both of said seat pieces being free along 15 their upper edges and supported in such manner that the upper ends of said seat pieces are both laterally slidable.

2. An improved union undergarment comprising a body portion and inner and outer seat flaps, one longitudinal edge of 20 each of which is secured to the body of the garment and the other longitudinal edges of which form, respectively, inner and outer edges of a seat opening, said free edges being 25 located on opposite sides of the median line of the garment, the upper edges of said seat flaps sloping downwardly from the median line toward the side of the garment, and being open and supported in such manner as to be laterally slidable.

3. An improved union garment comprising a body portion and inner and outer seat flaps, one longitudinal edge of each of 30 which is secured to the body of the garment, the other longitudinal edges of which are 35 free and form the seat opening, said free edges being located on opposite sides of the median line of the garment, one of said seat flaps being free along its upper edge, 40 a transverse strap having its ends secured to the body portion of the garment, said free upper edge of the said seat flap being slideable on said strap.

4. An improved union undergarment 45 comprising a body portion and inner and outer seat flaps, one longitudinal edge of each of which is secured to the body of the garment and the other longitudinal edges of which are free and form the sides of the 50 seat opening, said free edges being located on opposite sides of the median line of the garment, the upper edge of one of said seat

flaps being free, a transverse strap the ends of which are secured to the body portion of the garment and slope downwardly from 55 the median line toward the side of the garment, said seat flap being slidable on said strap.

5. An improved union undergarment comprising a body portion and inner and outer seat flaps, a longitudinal edge of each of which is secured to the body of the garment and the other side edges are free and form the sides of the seat opening, said free edges being located on opposite sides of the 60 median line of the garment, one of said seat flaps being free along its upper edge, a transverse strap one end of which is permanently secured to the body portion of the garment and the other end of which is detachably secured thereto, the free edge of 65 said seat flap being adapted to slide on said strap.

6. An improved union undergarment comprising a body portion and inner and outer seat flaps, one longitudinal edge of 70 each of which is secured to the body portion of the garment and the other longitudinal edges of which form the inner and outer sides of the seat opening, said sides of the 75 seat opening being located on opposite sides of the median line of the garment, the upper edges of both of said seat flaps being free, transverse straps secured at their ends to the body of the garment, the upper free edges of 80 said seat flaps being adapted to slide on said straps.

7. An improved union undergarment comprising a body portion and inner and outer seat flaps, one longitudinal edge of 90 each of which is secured to the body portion of the garment and the other longitudinal edges of which are free and form inner and outer side edges of the seat opening, which edges are located on opposite sides of the 95 median line of the garment, the upper edges of both of said seat flaps being free, transverse straps secured at their ends to the body of the garment, the upper free edges of 100 said seat flaps being adapted to slide on said straps, the outer ends of said straps being lower than the middle ends thereof.

In testimony whereof I affix my signature.

WILLIAM B. ROOD.
